UNITED STATES PATENT OFFICE.

HANS LIPPELT, OF LYNN, MASSACHUSETTS, ASSIGNOR TO GENERAL ELECTRIC COMPANY,
A CORPORATION OF NEW YORK.

DYNAMO-ELECTRIC MACHINE.

No. 919,604.

Specification of Letters Patent.

Patented April 27, 1909.

Application filed February 3, 1908. Serial No. 413,960.

To all whom it may concern:

Be it known that I, HANS LIPPELT, a subject of the Emperor of Germany, residing at Lynn, in the county of Essex, State of Massachusetts, have invented certain new and useful Improvements in Dynamo-Electric Machines, of which the following is a specification.

My invention relates to dynamo-electric machines, and consists in an improvement in the machine described in Patent No. 756,793, issued to me April 5, 1904. In that patent I described a dynamo-electric machine having an armature of the open-coil type with commutator and brushes arranged to maintain each armature-coil in circuit while cutting the flux of the field-poles; the field-magnet being arranged to give a substantially uniform induced voltage in the armature conductors as they pass the field-poles both under load and at no-load. My invention has to do with the commutation of such a machine, and comprises a number of features which will be specifically pointed out in the appended claims, but will best be understood by reference to the accompanying drawings, in which—

Figure 1 shows diagrammatically an end view of a machine arranged in accordance with my invention, both armature and field being developed along a straight line; Fig. 2 shows a diagrammatic plan view of the armature, the windings and commutator being developed on a plane surface; Fig. 3 shows a somewhat diagrammatic end view of the machine; Fig. 4 is an explanatory diagram of the positions of the poles; Fig. 5 is a diagram of the induced voltages in the armature conductors in a generator; Figs. 6 and 7 are explanatory diagrams; Fig. 8 is a diagram of induced armature voltages in a motor; Fig. 9 shows an end elevation of one of the main field poles; Fig. 10 shows a side elevation of the same; Fig. 11 shows an end elevation of a modified form of one of the main poles with the windings in cross-section; Fig. 12 is a similar view of one of the auxiliary poles; Fig. 13 shows a modified arrangement of the reactive coil employed for commutation purposes; and Fig. 14 is a cross-sectional view of the reactive coil suitably arranged.

Referring first to Fig. 1, 1, 2, 3, 4, 5 and 6 represent the main field-poles, which are unevenly spaced, and 7 and 8 represent auxil-

iary poles occupying the spaces left by the uneven spacing of the main poles. The auxiliary pole 7 is bifurcated so as to form two communicating poles 7', and the auxiliary pole 8 is similarly arranged. 9 represents a shunt winding magnetizing each of the main poles. The direction of current in the conductors of this winding is indicated in the conventional manner, and the polarities of the main poles due to the shunt winding are indicated by the letters N and S. 10 represents a series winding which surrounds all or a portion of the main poles, and which, it will be noted, opposes the shunt winding on certain poles and assists it on others. This series winding also magnetizes the auxiliary poles 7 and 8, a single coil serving to magnetize both the commutating poles formed by each auxiliary pole. The armature winding is of the open-coil type, as shown in Fig. 2, and comprises four coils, or rather four circuits of three coils each, 11, 12, 13 and 14. It will be understood that in practice a larger number of circuits or sets of coils may be employed, but four are sufficient for purposes of illustration. In Fig. 1 the directions of current-flow in the armature conductors are indicated conventionally, and it will be seen that three of the four sets of coils are in circuit. For cutting the armature coils into and out of circuit, brushes 15 and commutator segments 16 are provided. If the armature conductors are stationary they are connected to the brushes 15, while the commutator segments 16 are connected to collector rings 17, from which the armature current is led off by brushes 18. It will be noted that half the segments 16 have their ends 16' separated from the main portion of the segment, so as to form small auxiliary segments. This arrangement of segments and of the reactive coil 19, to which the segments are connected, are for purposes of commutation, as will be explained hereinafter.

Fig. 3 shows an end elevation of the machine, which figure will be understood from the above description of Figs. 1 and 2. The direction of rotation of the field-magnet, in the case of a generator, is indicated by the arrow.

It will be seen that the spacing of the main field-poles with respect to any one armature circuit is uneven. If any armature circuit is traced from one brush 15 through the conductors to the brush which forms the

other terminal of the circuit, and if the positions of the field-poles for the three coils of the circuit are indicated in superposition as for a single coil, the result will be as indicated in Fig. 4. From this figure it is seen that the main poles 1, 3 and 5, displaced as shown, form in effect a resultant north pole magnetized by the shunt winding 9. The series winding 10 on the poles 1 and 5 tends to produce a cross magnetization of the resultant pole formed by the three poles 1, 3 and 5, and if this series winding is properly proportioned, it will compensate for armature-reaction, which tends to produce an opposite cross-magnetization of the pole, or in other words, tends to weaken pole 1 and to strengthen pole 5. In addition to the turns on the main poles, the winding 10 comprises certain turns on the commutating poles 7' and 8', which lie at the tips of the resultant pole formed by the three poles 1, 3 and 5. The pole 8' is a north pole, while the pole 7' is a south pole, so that the effect of these commutating poles is to increase the strength of the resultant pole at one tip and weaken it at the other. If, now, we consider the voltage induced in a conductor passing under the resultant pole formed by the main poles 1, 3 and 5 and the commutating poles 8' and 7', which voltages will be the same as those actually produced in the set of coils forming each armature-circuit, it will be seen that the voltage-curve will be as indicated by the line 20 in Fig. 5, the irregularity at the pole-tips being caused by the flux of the commutating poles, indicated by the curves 21. If these poles were absent, the top of the curve 20 would be straight as indicated in dotted lines at 20'. The distance between the lines 22, above and below the zero-line of Fig. 5, represents the voltage at the armature terminals, the distance between the line 22 and the top of curve 20 representing the ohmic-drop in the armature. It will be seen that the voltages induced by the commutating poles are equal to the voltage-drop in the armature, but that the voltage due to one pole is added to the voltage induced by the main poles; and while the voltage induced by the other commutating pole opposes that of the main poles. Since both the ohmic drop in the armature and the flux of the commutating poles are proportional to the armature current, the voltage relation specified remains constant for all loads. The purpose of this arrangement of commutating poles will be understood by reference to Figs. 6 and 7, which are diagrams of the current-rise and fall in a machine without and with commutating poles.

In Fig. 6 the induced voltage is supposed to be uniform, as shown by the curve 20'. The points at which the armature coils are cut into and out of circuit are indicated by

the vertical lines 23 and 24, respectively. The curve 25 then represents the rise and fall of current in the conductor passing under the pole. When a coil is first cut into the circuit, the current does not rise instantaneously to its full value, on account of self-induction; but rises as shown by the curve 25. When the coil conductors reach the point 26, at which the induced voltage begins to fall, the current also begins to fall; and after passing the point 27, at which the induced voltage is equal to the voltage at the armature terminals, the current in the coil falls more rapidly, becoming zero at the line 24. If the coil is cut out of circuit exactly at the point indicated by the line 24, no sparking will result, because the current in the conductor at that instant is at zero; but in practice it is impossible to maintain this point exactly. It is shifted more or less by armature reaction with variations in load, so that ordinarily the coil will be cut out of circuit on one side or the other of the point indicated by the line 24. Since the current tends to vary rapidly in the coil on each side of this line, a brush-adjustment that is faulty to a comparatively small degree will produce sparking.

Fig. 7 shows the current in an armature-coil with a curve of induced voltage the same as shown in Fig. 5. At the entering-end, the curve 25 is steeper than in Fig. 6, meaning that the current rises in the coil more rapidly on account of the excess of voltage which is induced in it for a short time after it enters the field. At the outgoing-end the curve 25 is of a different shape from that of Fig. 6. Since the induced voltage at the outgoing-end falls off abruptly a certain amount and then is uniform for a certain length of time, the current-curve 25 falls abruptly at first, and then falls very gradually, being almost parallel to the zero line at the point at which the coil is cut out of circuit, represented by the line 24. Since the variation in current at this point is small, it is comparatively immaterial if the brushes are set properly, as for instance, so as to cut out the coil at the point indicated by the line 24'; for even at this latter line the current in the coil is small. Therefore, owing to the peculiar flux-distribution, no adjustment of the brushes with varying load is required, but satisfactory commutation is obtained with fixed brushes for no-load and full-load.

The curves above described relate to the machine running as a generator. If the machine runs as a motor, the voltage-curve is indicated by Fig. 8. In this case the armature terminal-voltage is in excess of the induced armature voltage by an amount equal to the ohmic-drop in the armature, and the field is strengthened by the commutating poles at the outgoing pole-tip and weakened at the incoming pole-tip, as indicated by the curves.

In order to decrease the self-induction of the armature-coils and thereby further to improve the commutation, the poles may be constructed as shown in Fig. 9,—*i. e.*, laminated in axial planes, instead of in circumferential planes in the usual manner. The poles may be built up of magnetic slabs 29 separated by non-magnetic, non-conducting sheets 30. In place of the slabs 29, thin plates 31 may be employed, particularly, at the end of the pole at which the armature-coil is cut out of circuit. This construction offers a high reluctance to the flux due to the armature-current, and consequently gives to the armature-coils a low reactance.

Fig. 10 shows a side view of a pole constructed as in Fig. 9.

The compensation of armature reactance by series windings on the unevenly distributed main poles has already been described. This arrangement is effective in neutralizing armature reaction on the resultant pole formed by the several unevenly spaced poles. If it is desired to compensate for armature reaction on each individual pole, it may be done in the manner shown in Fig. 11. In this figure, in addition to the main shunt-coils 9 and series coils 10, auxiliary coils 32 are embedded in the pole near its face and connected so as to tend to cross-magnetize the pole-face, thereby opposing the cross-magnetizing tendency of the armature current.

Fig. 12 shows a suitable construction for one of the auxiliary poles forming a pair of commutating poles magnetized by a signal series coil 10. Armature reaction on the auxiliary poles may be compensated for, if desired, by auxiliary windings 32, similar to those applied to the main poles in Fig. 11.

Now referring again to Fig. 2, the operation of the reactive coil 19, which has already been referred to, will be explained. In Fig. 2 this coil is shown inserted in the connection between one of the collector rings 17 and the commutator segments connected to this collector ring. One terminal of the coil is connected to the main commutator segment 16, while other terminals are connected to the auxiliary segments 16'. If the commutator in Fig. 2 is supposed to be moving from left to right, it will be seen that the coils 11 will next be cut out of circuit, while the coils 14 will be cut into circuit. It will further be seen that one of the brushes 15, connected to the coils 11, will reach one of the auxiliary commutator segments 16' at the same time that one of these auxiliary segments is reached by a brush connected to the coils 14. The coils 11 and 14 are consequently simultaneously connected to the reactive device 19, and, in fact, are connected in parallel through this device. By means of this connection the decrease in current in the coils 11, as they pass out from the

field-poles induces in the reactive winding a voltage which tends to assist the rise in current in the coils 14 as they are cut into circuit, while the rise of current in the coils 14 tends to increase the rapidity with which the current diminishes in the coils 11. In other words, the mutual induction between the coils 11 and 14 is increased by means of their parallel connection through the reactive coils, so that current is shifted from one coil to the other, as one is cut out of circuit and the other cut in, without the production of reactive voltages at the coil-terminals, which would tend to result in sparking.

The reactive coil need not be connected at all to the main commutator segment 16, but may be connected as shown in Fig. 13. The operation is substantially the same as has been described in connection with Fig. 2.

The reactive coil may conveniently be mounted on the shaft of the machine between the commutator and the collector rings 17, as is indicated in Fig. 14.

I do not desire to limit myself to the particular construction and arrangement of parts here shown, but aim in the appended claims to cover all modifications which are within the scope of my invention.

What I claim as new and desire to secure by Letters Patent of the United States, is—

1. In a dynamo-electric machine, a multipolar field-magnet, an armature having a winding of the open-coil type, and a commutator and brushes for the armature winding arranged to maintain each coil in circuit while it is cutting the flux of the field-poles, said magnet having main poles unevenly spaced with respect to the armature winding and provided with both shunt and series windings and auxiliary commutating poles occupying the spaces left by the uneven spacing of the main poles and provided with series windings.

2. In a dynamo-electric machine, a multipolar field-magnet, an armature having a winding of the open-coil type, and a commutator and brushes for the armature winding arranged to maintain each coil in circuit while it is cutting the flux of the field-poles, said magnet having main poles unevenly spaced with respect to the armature winding and provided with both shunt and series coils and auxiliary commutating poles occupying the spaces left by the uneven spacing of the main poles and provided with series windings, the series winding on the main poles being connected to oppose the shunt winding on some of said poles and to resist it on others, whereby armature reaction is compensated for.

3. In a dynamo-electric machine, a field-magnet, a field winding thereon, an armature having a winding of the open-coil type, a commutator and brushes for the armature winding arranged to maintain each coil in

5 circuit while it is cutting the flux of the field-poles, a reactive device, and connections between said device and the commutator and brushes whereby the armature coils about to be cut out of circuit and the coils about to be cut into circuit are simultaneously connected to said reactive device.

4. In a dynamo-electric machine, a field-magnet, a field winding thereon, an armature 10 having a winding of the open-coil type, a commutator and brushes for the armature winding arranged to maintain each coil in circuit while it is cutting the flux of the field-poles, a reactive device, and connections 15 between said device and the commutator and brushes whereby the armature coils to be cut out of circuit and the coils about to be cut into circuit are simultaneously connected in parallel through said reactive device.

5. In a dynamo-electric machine, a field-magnet, an armature having a winding of the open-coil type, a commutator and brushes for the armature winding arranged to maintain each coil in circuit while it is cutting the flux of the field-poles, said field-magnet being arranged and provided with windings 25 adapted to induce in each armature coil a substantially uniform voltage of a certain amount during the greater part of the time it is in circuit and a substantially uniform 30

voltage of a different amount for a small part of said time just before it is cut out of circuit, a reactive device, and connections between said device and the commutator and brushes 35 whereby the armature coils about to be cut out of circuit and the coils about to be cut into circuit are simultaneously connected to said reactive device.

6. In a dynamo-electric machine, a multi-polar field-magnet, an armature having a winding of the open-coil type, and a commutator and brushes for the armature winding arranged to maintain each coil in circuit while it is cutting the flux of the field-poles, 40 said magnet having main poles unevenly spaced with respect to the armature winding and provided with main exciting windings and auxiliary poles occupying the spaces left by the uneven spacing of the main poles and 45 bifurcated so that each auxiliary pole forms a pair of commutating poles, and a series-connected coil surrounding each auxiliary pole and magnetizing both of the commutating poles formed thereby. 50 55

In witness whereof, I have hereunto set my hand this twenty-ninth day of January, 1908.

HANS LIPPELT.
